UNITED STATES PATENT OFFICE

2,544,839

APPARATUS FOR EFFECTING THE HARDENING OF DEPOSITS OF INK AND LIKE COMPOSITIONS

Jess D. Klopfenstein, Chicago, Ill., assignor to
The Meyercord Co., a corporation of Illinois

Application November 1, 1946, Serial No. 707,228

5 Claims. (Cl. 34—122)

1

This invention relates to apparatus for effecting hardening of deposits, coatings and films of ink and like compositions, and more particularly to apparatus for subjecting traveling sheet or web material having ink deposits thereon to the action of a treating agent for effecting the rapid hardening, or drying, of the ink deposits.

In the printing of paper and other sheet and web material with relatively heavy deposits of ink, or other compositions that dry, or harden, rather slowly, the time required for the drying, or hardening, gives rise to serious manufacturing problems. For instance, in the manufacture of decalcomania transfers, the drying time may range from over night to as long as five days, depending upon the fullness of the form, the color of the ink being run, the composition and properties of the color that may have been previously applied to the sheet, and numerous other factors. A considerable amount of floor space must be used in the storage of the printed sheets, and particularly is this true where the printed sheets have to be racked in comparatively shallow stacks. In addition, there is the labor expense incident to handling the stacked sheets and periodically folding and winding the sheets to give the printed matter access to the air and thus effect the drying more uniformly and more rapidly.

It has now been proposed that the freshly printed sheets be subjected to the action of sulphur di-chloride in vapor form, since the action of sulphur di-chloride has been found to effect a very rapid drying of ink compositions. The drying, or hardening effect, has been found to be due to the chemical reaction between sulphur di-chloride and the organic compounds present in the ink compositions. In the case of inks containing drying oils, such as linseed oil and other oils of an unsaturated character, it is probable that the sulphur di-chloride adds on at the double bond and that polymerization thereafter occurs. However, even where there are no unsaturated compounds present, a substitution of the sulphur di-chloride for an H atom in the hydrocarbon compound apparently takes place, leaving both sulphur and chlorine bound in the molecule. While the reaction of sulphur di-chloride with organic compounds containing unsaturated linkages by addition to the double bond is much more rapid than the reaction with a saturated compound by replacement of a hydrogen, the final products in both cases are essentially the same. A relatively dry, non-tacky, hard film or deposit is formed by the action of the sulphur di-chloride within a relatively short time, of the

2

order of ten seconds or less in the case of the unsaturated type of hydrocarbon, and of the order of thirty seconds or less in the case of the saturated hydrocarbon compounds.

3 The use of sulphur di-chloride for the hardening or drying of ink and like compositions, however, presents certain problems in that sulphur di-chloride has a deleterious effect upon the paper itself where the printing is done on paper. My 10 present invention is directed to the solution of this problem by the provision of means for regulating the time of contact of the sulphur di-chloride vapor with the printed surface and reducing or entirely eliminating contact of the vapor 15 with the other surface of the paper. The apparatus of my invention also provides for dissipating the excess of sulphur di-chloride so as to reduce the amount of the sulphur di-chloride left in association with the printed paper after treatment 20 thereof.

In accordance with the principles of my present invention, I provide a multi-compartment chamber into which a printed material, either in sheet or in continuous web form, is passed and within 25 which the inked surface is subjected to the action of sulphur di-chloride for a predetermined length of time. The sheet or web as it passes through the chamber is supported by or held against an imperforate surface, preferably curved, so as to reduce the contact of the unprinted side of the sheet or web with the sulphur di-chloride vapors. In one form of my invention, this is accomplished by means of grippers that hold the sheet against the surface of a revolving drum or roll, while in 30 the case of the continuous web, the web is tensioned as it passes over a curved surface, so as to be held tightly thereagainst.

Penetration of the sulphur di-chloride vapors into the sheet through the surface on which the 35 ink is deposited may be prevented or reduced in extent by providing a coating over the paper before the ink is deposited thereon. In the case of decalcomania transfers, such a coating is normally present since a layer of dextrin, or dextrin and starch, is provided to enable the transfer, by wetting, of the decalcomania from the paper to the surface to which the decalcomania is to be applied.

It is therefore an important object of this 40 invention to provide apparatus suitable for use in the drying or hardening of films or deposits of ink and like compositions by subjecting such films or deposits to the action of a treating agent, such as sulphur di-chloride vapor.

It is a further important object of this inven-

tion to provide apparatus including a multi-compartment chamber through which sheet or web material may be passed after it has been printed, and wherein the printed matter is subjected to the action of a vapor, such as sulphur di-chloride, to dry, or harden, the same, means being provided for limiting the contact of the treating vapors to the printed surface only, and other means being provided for dissipating the excess or unused portion of the treating vapors from the sheet or web material to lessen any deleterious action of the treating vapors upon the material of the sheet or web itself.

Other and further important objects of this invention will be apparent from the disclosures in the specification and the accompanying drawings.

On the drawings:

Figure 1 is a schematic side elevational view of a printing press and of apparatus embodying my invention, associated therewith for drying or hardening the ink on the printed sheets as they come from the press.

Figure 2 is a schematic side elevational view of a continuous web printing press of a multi-color type, having associated therewith apparatus embodying the principles of my invention.

Figure 3 is an enlarged side elevational view of the apparatus illustrated in Figure 1, with parts broken away and in section.

Figure 4 is an enlarged fragmentary side elevational view of a portion of the apparatus illustrated in Figure 2, with parts broken away and in section.

Figure 5 is an end elevational view of the apparatus illustrated in Figure 4.

Figure 6 is an enlarged fragmentary sectional view of a decalcomania sheet illustrating a stage in its manufacture after at least one printing operation but before the final operations have been performed.

As shown on the drawings:

The reference numeral 10 indicates generally a printing press of the type wherein sheets, such as the sheets 11, rather than a continuous web, are fed through the press and are printed during passage therethrough. The printing press 10, which is illustrated more or less schematically, includes an inking roller 12, to which ink is fed by means of a plurality of ink distributing rollers 13. As the sheet 11 passes over a backing roll 14 into the nip between said roll and the inking roll 12, a deposit of ink is left on the surface of the sheet 11. The sheets 11 are transferred from the roll 14 to a skeleton transfer cylinder 15 that carries gripper bar chains 17 that serve to transfer the printed sheets face up onto a plurality of traveling belts 19. The belts 19 are tensioned around a pair of rolls 20 and 21, of which one, such as the roll 20, may suitably be driven. From the conveyor belts 19, the sheet is delivered onto stationary supports 22, which may be in the form of spaced metal strips having their rear ends positioned under the roll 21 for reception of the sheets as they pass thereover.

The supports 22 serve to transfer the sheets 11 from the printing press 10 to apparatus, indicated generally by the reference numeral 23, wherein the printed matter is dried, or hardened, by the action of a treating agent, such as sulphur di-chloride vapor. In order to progress the sheets 11 in proper spaced sequence and in synchronism with the movement of the sheets through the press 10, means synchronized with the operation of the press are provided, including moving fin-

gers 24 that engage the trailing edges of the sheets 11 and move them along the supports 22. Advancing means of a type suitable for this purpose are well known in connection with printing presses and like pieces of equipment.

The apparatus 23 includes a cylindrical roll 25 mounted upon a shaft 26, on one end of which is secured a gear 27. Said gear 27 meshes with a gear 28 mounted on a stub shaft 29 that is driven through a sprocket 30, also mounted on said stub shaft 29, and a chain 31 from a sprocket 32 mounted on the same shaft 33 with the roll 18. The surface speed of the roll 25 is thus synchronized with the speed of travel of the sheets 11 through the printing press 10.

As is best shown in Figure 3, the shaft 26 is supported in bearings 34 mounted upon supporting side frames 35. The roll 25 is provided with sheet gripping means 36, which may be of the conventional construction known in the printing press art. As illustrated, there are three such sets of gripping means 36 spaced about the periphery of the drum 25. As a sheet 11 is advanced by fingers 24, the leading edge of the sheet 11 comes in contact with one of the gripping means 36 and that edge is then clamped by such means to the periphery of the roll 25. One such sheet 11 is shown in Figure 3 in the clamped position and another sheet 11 is shown in its released position about to leave the roll or drum 25. Guiding means 37 serve to guide the released sheet 11 to a conveyor indicated generally by the reference numeral 38. The gripping means 36 thus serve to hold the printed sheet 11 upon the surface of the drum 25, with the printed surface uppermost and the opposite surface in contact with the surface of said drum 25. The conveyor 38 delivers the dried sheets to a table 39, on which the sheets are accumulated in a stack 8.

A chamber, indicated generally by the reference numeral 40, is supported about the upper portion of the drum 25 to enclose the upper half, or so, of said drum, for its full width. Said chamber 40 comprises a generally curved outer housing 41, the lower edges of which, as at 42 and 43, are spaced slightly from the periphery of the drum 25 to provide an entrance opening 44 and an exit opening 45, respectively. The housing 41 may suitably be formed of sheet metal, with its lower edges rolled or beaded. A portion, indicated at 46, of the housing 41 adjacent its edge 43 lies in closely spaced conforming relationship to the periphery of the roll 25 to provide a relatively elongated exit passageway 45a, the purpose of which will later appear.

Said chamber 40 also includes an inner housing 47, conforming in general with the contour of the housing 41 and spaced therefrom to provide a compartment C. Said inner housing or partition 47 also forms with the periphery of the drum 25 an inner chamber C'. The lower edges of said inner housing 47 are positioned relatively closer to the periphery of the drum 25 than the outer housing edges 42 and 43 to provide a narrow entrance 48 and a narrow exit 49, both lying inside and upwardly of the entrance passages 44 and 45, respectively.

The inner housing or partition 47 and the outer housing 41, thus, in effect provide nested arcuate baffles with their terminal edges closely spaced from the backing surface afforded by the roll 25, with which said housing 47 and 41 define an inner treating chamber and an outer exhausting chamber in restricted communication with each other only at the terminal edges of the

entrance 48 and the exit 49 adjacent said backing surface.

The outer chamber C of said chambers is connected at its upper portion by means of a pipe or conduit 50 with an exhaust fan 51, which serves to apply a slight draft to said outer chamber C. The inner chamber C', which is the main treating chamber, is supplied with the treating vapor by means of a pipe 52 leading from a vapor generator 53 and having branch pipes 54, 54a and 54b that are perforated and that extend across said inner chamber C'. The vapor generator 53 (Fig. 3) comprises a receptacle for containing liquid sulphur di-chloride, indicated generally at 55, or other liquid that is to be vaporized. Air is let into said receptacle 53 below the level of the liquid 55 through a pipe 56 for discharge through a perforated manifold 57. As the air passes up through liquid 55, the liquid is vaporized into the stream of air and the admixed air and vapor pass upwardly through the pipe 52 and through the branches 54, 54a and 54b into the chamber C'. Within said inner chamber C' the vapors are largely confined, but to prevent any substantial escape of vapors through the entrance and exit openings 48 and 49 to the atmosphere, a slight suction is placed by means of the exhaust fan 51 upon the interior of the outer chamber C, whereby air is drawn inwardly through the entrance passages 44 and 45. Any vapors tending to escape from the inner chamber C' are, therefore, drawn into the air stream entering the outer chamber C and thence exhausted through the fan 51 to a scrubber (not shown) or other equipment for the recovery or disposition of the unused sulphur di-chloride vapors. Only a sufficient amount of draft to prevent the escape of the vapors into the atmosphere is applied.

By making the inner entrance and exit passages 48 and 49 very narrow as compared with the outer entrance and exit openings 44 and 45, there is very little tendency to draw the treating vapors from the inner chamber C' into the outer chamber C. The exit passageway 45a is purposely elongated so that the time of contact between the entering air stream and the treated sheet 11 will be sufficiently long to dissipate any treating vapors associated with the sheet 11 as it leaves the drum 25. In this way, both the escape of the treating vapors to the surrounding atmosphere and also the clinging of the treating vapors to the surface of the treated sheets 11 are largely eliminated.

In the operation of the apparatus illustrated in Figures 1 and 3, the sheets 11 are fed more or less automatically into the printing press 10 for receiving an ink impression from the inking roller 12. The sheets, one at a time, are advanced through the press 10 onto traveling belts 19 and then onto the supports 22, where the fingers 24 automatically engage the trailing edges of the sheets 11 and advance them into the vapor treating apparatus 23.

As the individual sheets 11 come into contact with the drum 25, the timing is such that the leading edge of the sheet is engaged by one of the gripping devices 36 and held thereby against the periphery of the drum 25 until the sheet has passed through the gas treating chamber and is released at the delivery side of the drum. The speed of rotation of the drum 25 is such that the passage of a sheet 11 through the treating chamber requires no more time than is sufficient to effect the hardening, or drying, action. In general, the total length of time to which the in-

dividual sheets 11 are subjected to the mixed air and sulphur di-chloride vapors is not over about ten seconds, and generally in the neighborhood of two or three seconds.

In Figures 2, 4 and 5, there is shown apparatus for the printing and drying of a continuous web, instead of sheets, as described in connection with Figures 1 and 3. The reference numeral 60 indicates generally a multi-color press comprising separate sets of printing roll stands 61, 62 and 63. Each of said sets includes a backing roll 64 and an inking roller 65, between which a continuous web 66 is drawn. A wound roll 67 constitutes the source of supply of the web 66. Said roll 67 is mounted upon an unwinding stand 68. The web 66 is led from the roll 67 through a number of guide and tensioning rolls 69 and thence through the printing press stands 61, 62 and 63, from the last of which the web is led over a guide roll 70 to a re-wind stand 71 where the web is wound up into a roll 72.

A gas treating chamber, indicated generally by the reference numeral 73, is mounted between the successive press stands 61 and 62, and 62 and 63, and between the press stand 63 and the re-wind stand 71. The treating chambers 73 are supplied with a mixture of air and sulphur di-chloride vapors from a vapor generator 74, similar to the generator 53 already described. The admixture of air and sulphur di-chloride vapors is conducted from the generator 74 through a manifold pipe 75, from which individual branch pipes 76 lead to the gas chambers 73. The exhaust from said gas chambers 73 is conducted by means of branch pipes 77 to an exhaust manifold 78 and thence to an exhaust fan or blower 79 driven by means of a pulley and belt 81.

The construction of the gas chambers 73 is shown in greater detail in Figure 4, and will now be described. Said chamber 73 comprises an outer housing 82 and an inner housing or partition 83, mounted in combination with a backing plate 84. Said backing plate 84 comprises a curved, imperforate sheet, which may suitably be formed of highly polished sheet metal and provided with an upturned peripheral flange 85 to impart rigidity thereto. The curvature of the backing sheet 84 is such that the web 66 is held thereagainst in close contact with the under surface of said backing sheet. Guide rolls 86 and 87 at the entrance and exit ends of the gas chamber aid in maintaining the web 66 under slight tension in surface contact with the surface of said backing sheet 84 during its passage thereover. The back side or unprinted side of the web 66 is thus protected against contact with the sulphur di-chloride vapors within the inner chamber, indicated at 87, formed between the inner housing 83 and the backing sheet 84.

The outer housing 82 is provided with an edge 88 lying in closely spaced relationship to the guide roll 86 and forming therewith an entrance 89 for the passage of the web 66. Toward the exit end of the gas chamber 73, the outer casing 82 is offset upwardly to provide an elongated plate portion 90 lying in closely spaced conforming relationship to the adjacent portion of the backing plate 84 and forming therewith an elongated passage 91 through which the web 66 passes after leaving the inner gas treating chamber 87. The inner housing 83 is provided with inturned edge portions 92 and 93 providing, respectively, very narrow inlet and outlet openings 94 and 95 for the paper web 66. Said edges 92 and 93 are more closely spaced with respect to

the backing plate 84 and the web 66 traveling thereover than are the outer casing end edges 88 and 90. Consequently, there is less tendency for the treating vapors to be drawn through said openings 94 and 95 into the outer chamber 96 than there is for air from the outside to be drawn through the openings 88 and 91.

In the operation of the apparatus illustrated in Figures 2, 4 and 5, the web 66 passes successively through the printing press sections 61, 62 and 63 and as it leaves each of the printing sections passes through a gas treating chamber 73. Since the printing sections are all driven at the same speed, the web 66 maintains a constant linear speed as it passes through the apparatus. In general, the speed of the web is of the order of 10 to 30 feet per second. At each of the successive printing sections 61, 62 and 63, a different color or design may be imprinted upon the under surface of the web 66. Each such color or design must be dried, or hardened, before the web passes through a subsequent printing section or is wound up into the roll 72.

The drying, or hardening, of the printed surface of the web is effected as the web passes through the successive treating chambers 73, due to the action previously described. The other surface of the web 66, namely that which does not receive the printed matter, is firmly held against the backing surface 84 due to the arrangement of the rollers 86 and 87 and the curved nature of said backing plate 84. The unprinted surface of the web is therefore protected against the action of the sulphur di-chloride vapors within the inner treating chamber 87.

Furthermore, as the web 66 passes out beyond the exit edge 93, not only is the small amount of sulphur di-chloride vapor that may escape through the restricted exit opening 95 pulled away from the sheet by the exhaust placed upon the outer chamber 96, but air is drawn along the elongated passage 91 to purge the sheet of any residual sulphur di-chloride vapor that may be associated therewith. The result is that the sheet leaves each treating chamber 73 with a minimum of excess sulphur di-chloride vapor associated therewith, so that there is little likelihood of any deleterious action on the paper itself as a result of the vapor treatment with sulphur di-chloride.

The time of contact between the sulphur di-chloride vapors and the printed matter on the sheet is such that the printed matter is dried, or hardened, to leave a relatively non-tacky imprint thereon before another impression of color, or ink, is received by the web, or before the web is wound up into the final roll 72.

The advantages of the equipment above described is that successive imprints on the same sheet or web can be made without intermediate slowing up or stoppage of the progress of the sheet or web through the printing press, or press sections. According to present practice in the manufacture of decalcomania transfers, a drying or hardening period of from over night to five days is required. The apparatus of my invention does away entirely with the necessity of individual racking of the sheets, thus making more of the floor available for production. Heavier films of ink may be laid on the sheet or web than was previously possible, assuring greater brilliancy of the color. Also, a heavier film of ink per impression means fewer times through the press to arrive at a specified thickness of impression.

By placing treating chambers between units 75

of a multi-color press, a heavier film of ink may be applied without having to give consideration to the rotation of color or to the trapping of color.

In the case of the manufacture of decalcomania transfers, as previously explained, the printing is done upon the coated side of a paper coated with dextrin, or with dextrin and starch. This is illustrated in Figure 6, in which the reference numeral 100 indicates the base, which may be a paper sheet or web, the reference numeral 101 indicating the coating of dextrin or of dextrin and starch, and the reference numeral 102 indicating a solid ink backing coat and the reference numeral 103 indicating an ink or color impression thereon. Inasmuch as the uncoated side 104 of the base 100 would lie against and be supported by a backing plate, as explained in connection with the operation of apparatus above described, only the dextrin coating 101 would be directly exposed to the action of the sulphur di-chloride vapors. It has been found that a dextrin, or dextrin and starch coating, such as used in decalcomania transfers affords considerable resistance to the penetration of the sulphur di-chloride vapors into the body of the paper base 100, thus protecting the material of the base from the deleterious action of the sulphur di-chloride vapors. Other types of coatings, such as the starch coatings applied to book papers and the like, serve a similar function of presenting a barrier to the penetration of the sulphur di-chloride vapors into the body of the sheet or web.

Consequently, by the use of a suitably coated paper, by the provision of a rigid, imperforate backing plate or surface over which the uncoated side of the sheet or web may be held during passage of the sheet or web through the treating chambers, and by the provision of an elongated exit passage along which fresh air is drawn over the treated sheet to purge the same of any residual sulphur di-chloride vapors, any otherwise deleterious action of the sulphur di-chloride vapors on the sheet is largely avoided.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In apparatus of the class described, driven means defining a backing surface on which sheet-like material may be moved, a housing having nested arcuate baffles providing parallel terminal edges closely spaced from said backing surface and defining therewith an inner treating chamber and an outer exhausting chamber in restricted communication with each other only at said terminal edges adjacent said backing surface, means for supplying a treating agent in vapor form to said treating chamber, means for withdrawing unused treating agent from said exhausting chamber and means carried by said driven means for engaging said sheet-like material to hold the same against said backing surface to expose only the opposite surface of said material to said treating vapor.

2. Apparatus for treating freshly printed surfaces of successively advanced separate sheets comprising a member providing a backing surface against which said sheets are held, gripping

means carried by said member for clamping one surface of said sheets against said backing surface during travel of said sheets, means confining a treating agent in vapor form in contact with the other surface of said sheets while held against said backing surface and means creating a flow of air over said sheets as the same enter and leave said confining means.

3. In apparatus for treating freshly printed surfaces of successively advanced separate sheets, means comprising a driven member providing an imperforate curved backing surface against which said sheets are held, gripping means carried by said member for holding one surface of said sheets against said backing surface during travel of the sheets, means confining a treating agent in vapor form in contact with the other surface of said sheets while held against said backing surface, means for driving said driven member and means creating a flow of air over said sheets as the same enter and leave said confining means.

4. In apparatus for treating freshly printed surfaces of successively advanced separate sheets, a member providing a backing surface against which said sheets travel, gripping means carried by said member for holding one surface of said sheets against said backing surface during further travel of the sheets, means including a housing having entrance and exit lips closely spaced from said backing surface confining a treating agent in vapor form for contact with the other surface of said sheets while held against said backing surface and means creating a flow of air over said sheets as the same enter and leave said confining means.

5. In apparatus for treating freshly printed surfaces of successively advanced separate sheets, a treating chamber comprising a member providing an imperforate backing surface for receiv-

5
